UNITED STATES PATENT OFFICE.

ALEXANDER McLEESTER, OF PHILADELPHIA, PENNSYLVANIA, ASSIGNOR TO
COLLINS & McLEESTER, OF SAME PLACE.

DESIGN FOR TYPE.

Specification forming part of Design No. 5,342, dated October 31, 1871.

To all whom it may concern:

Be it known that I, ALEXANDER McLEESTER, of the city and county of Philadelphia, Pennsylvania, have originated and produced a new and original Design for Printing-Type, of which the following is a specification:

The nature of my design is fully represented

in the accompanying photographic impressions to which reference is made.

What I claim as my invention is—
The design for printing-type, as shown.

Witnesses: ALEX. McLEESTER.

DAVID BEITLER,
EUG. H. MUNDAY.
